TUMBLERLESS SAFE

Henry C. Whittall, Oakland, Calif., assignor of twenty-four per cent to Harold G. Geltz, Oakland, and twenty-four per cent to Walter H. Kassebohm and twenty-four per cent to Thomas H. Harvey, both of Berkeley, Calif.

Application December 31, 1946, Serial No. 719,558

5 Claims. (Cl. 70—293)

1

This invention relates to a locking mechanism, and more particularly to a combination safe.

An object of the invention is to provide a combination safe which is substantially foolproof against unwarranted opening.

Another object of the invention is to provide a tumblerless safe of the combination type.

A further object of the invention is to provide a compact, efficient combination safe particularly adapted for residential use as a wall or floor safe.

Other objects and advantages of the invention will be apparent from the following description taken in conjunction with the drawings forming a part of this specification, and in which:

Figure 1 is a view in section of the safe embodied in the invention, showing the mechanism in locking position;

Figure 2 is a top plan view of the safe;

Figure 3 is a view in section taken along lines 3—3 of Figure 1; and

Figure 4 is a view in section taken along lines 4—4 of Figure 3, showing the mechanism in unlocking position.

Referring to the drawings for more specific details of the invention, the safe is comprised of a cylindrical casing, or safe body, 10 having welded thereto a base plate 12. The casing 10 has an inner circumferential locking groove 14 and is provided with an inner shoulder 16 adapted to receive in abutting relation an end plate indicated generally at 18, said end plate being provided on the underside with a centrally located boss 20, six bosses 22 equidistantly spaced therefrom, and three depending lugs 24 spaced 120° apart. The boss 20 has therethrough a double diametral drill hole 26 providing a shoulder 28, and the bosses 22 are each provided with a double diametral drill hole 30 providing a shoulder 32. For a purpose hereinafter disclosed, one of the bosses 22 and the axis of the drill hole therethrough is located 65° from one of the adjacent bosses and axes and 55° from the other adjacent boss and axis, as indicated in Figure 3, the remaining bosses and drill hole axes being mutually spaced 60° apart.

A multi-diametral main spindle 34, having a flange 36 adapted to seat on the shoulder 28 of the end plate 18, and a centrally disposed drilled hole 38, is provided with an annular groove 40, a conical cam surface 42, another annular groove 44, a shoulder 46, a square portion 48, and a threaded end 50, while a multi-diametral spindle 52, having a flange 54 adapted to seat on one of the shoulders 32 of the end plate 18, is provided

2

for each of the drill holes 30, each of said spindles having a centrally disposed drilled hole 56, a shoulder 58, a square portion 60, and a threaded end 62.

5 The main spindle 34 is provided with a knurled knob 64 having the shank thereof press-fitted into the drilled hole 38, said knob having an indicating arrow 66 inscribed in the upper surface thereof, said arrow being adapted upon the rotation of the knob to orient said knob in relation to indicia 68 inscribed in the surface of the end plate 18. The smaller spindles 52 are each provided with a knurled knob 70 having the shank thereof press fitted into a drilled hole 56, said knobs having an identifying numeral inscribed in the upper surface thereof, as shown in Figure 2, together with an indicating arrow 72, said arrow being adapted upon the rotation of a knob to orient said knob in relation to indicia 74 inscribed in the surface of the end plate 18 circumferentially adjacent the drilled holes 56.

20 A pair of matching locking plates 76, having a centrally disposed square aperture are secured on the square portion 48 of the main spindle 34 in abutting relation to the shoulder 46 of said spindle by a retaining plate 78 threaded on the end 50 of the spindle, said retaining plate having wrench engaging apertures 80. The plates 76 are cut away at predetermined peripheral locations to provide six teeth 82, said teeth being equidistantly spaced apart with the exception that one of said teeth is located 65° from the adjacent tooth at one side thereof and 55° from the adjacent tooth at the opposite side thereof, as indicated in Figure 3, the angular spacing of said teeth corresponding to the aforescribed angular spacing of the bosses 22 and the axes of the holes 56 therethrough. The retaining plate 78 serves to reinforce the locking plates 76 which are provided in duplicate for a similar reinforcing purpose.

25 A plurality of identical locking plates 84 and a single combination locking plate 86, each having a centrally disposed square aperture, are secured on the square portion of each of the spindles 52 by a lock washer 88 and a nut 90. The combination locking plate 86 has eight identical slots 92 equally spaced apart in the periphery thereof, said slots being adapted to selectively receive the teeth 82 of the locking plates 76. Each 30 of the locking plates 84 has a single slot 94, said slots being identical to each other and to the slots in plate 86, and being arranged in alignment with each other and with one of the slots 92 in plate 86.

35 Three drill holes 96 spaced 120° apart are pro-

vided through a wall of the central boss 20 normal to the spindle 34 and each of said holes is in alignment with a drilled hole 98 in the depending lugs 24 of the end plate 18. A bolt 100 having a conical end 102 is slidably supported in each set of aligned holes 96 and 98, said bolts being of greater length than the distance between the periphery of the drilled hole 26 and the outer surface of the lugs 24. Each bolt 100 has a transverse drilled hole therethrough in which a cotter pin 104 is inserted to inhibit movement of a washer 106, sleeved on the bolt in abutting relation to said cotter pin, under the action of a coil spring 108 held in compression between the washer and a lug 24 of the end plate.

A cover 110 having three notches cut therein to allow for the passage therethrough of the bolts 100 is secured to the lugs 24 by machine screws 112.

When the mechanism is in the locking position of Figure 1, the end plate 18 is secured to the casing 10 by the bolts 100 which extend into the locking groove 14 and are held in said position by the spindle 34 against the retractile action of springs 108. The spindle 34 is held against upward movement, since the teeth 82 of the locking plates 76 are out of registry with the slots 92 and 94 of the plates 84 and 86 carried by the spindles 52, and the plates 76 are, therefore, obstructed by the plates 84 and 86.

Upon rotating the knob 64 of the main spindle and the knobs 70 of the smaller spindles to bring indicating arrows 66 and 72 into alignment, respectively, with a predetermined unit of the indicia 68 and 74, the plates 76 and the plates 84 and 86 may be thus rotated to bring the teeth 82 into alignment with the slots 92 and 94 of the plates 84 and 86. The knob 64 may then be lifted to move the spindle 34 outwardly of the end plate 18 to move the plates 76 upwardly into the position of Figure 4, thus allowing the bolts 100 to be retracted from the locking groove 14 as the conical ends of the bolts move along the cammed surface 42 of the spindle 34 under the action of the springs 108. The end plate 18 may then be lifted free of the casing 10.

To restore the mechanism to the locking position of Figure 1, the end plate is replaced on the shoulder 16 of the casing, and the spindle 34 is depressed to force the conical ends of the bolts 100 to move from the annular groove 44, along the cammed surface 42, and into the annular groove 48 of the spindle, thus extending the opposite ends of the bolts into the locking groove 14. The spindles 64 and 70 are then haphazardly rotated to bring the teeth of the locking plates 76 out of alignment with the slots of the smaller locking plates.

Due to the non-uniform spacing of the teeth 82 of the plates 76, and the corresponding spacing of the spindles 52 and the locking plates carried thereby, there is but one position of the knob 64 in which the teeth 82 will be in unlocking alignment with the slots of the smaller locking plates. Thus, with the embodiment of the invention shown in the drawing, there is one combinative setting of the knobs 64 and 70, out of a possible 6,291,456 such settings, which will affect an unlocking of the safe.

Since the orientation of the locking plates 76 on the square portion 48 of the spindle 34 may be changed to any of four positions, and the orientation of the plates 84 on the square portions 60 of spindles 52 may be changed to a like number of positions, it is apparent that the single unlocking

combination of the safe may be varied at will by the user to any of 65,536 combinations, only one of which will be an unlocking combination at any one time.

The preferred embodiment of the invention has been shown and described, but it is understood that this embodiment is subject to modification within the spirit of the invention and the scope of the appended claims.

What I claim as new and desire to secure by Letters Patent is:

1. A safe comprising a casing, an end plate, and a locking mechanism, said mechanism comprising a locking groove in the casing, a centrally disposed rotatable and slidable spindle carried by the end plate, a plurality of slidable bolts carried by the end plate, the inner ends of said bolts abutting said spindle and the outer ends of said bolts being adapted to extend within the locking groove to secure the end plate to the casing, spring means to urge said bolts inwardly toward said spindle, means operable upon a predetermined rotational orientation of said spindle to allow said spindle to be moved outwardly of said end plate, and a cam surface on said spindle adapted to allow an inward movement of said bolts to free the ends thereof from said locking groove upon the outward movement of said spindle.
2. A safe comprising a casing, an end plate, and a locking mechanism, said mechanism comprising a locking groove in the casing, a centrally disposed rotatable and slidable spindle carried by the end plate, a plurality of slidable bolts carried by the end plate, the inner ends of said bolts abutting said spindle and the outer ends of said bolts being adapted to extend within the locking groove to secure the end plate to the casing, spring means to urge said bolts inwardly toward said spindle, a peripherally toothed plate carried by the inner end of said spindle, a plurality of rotatable spindles carried by the end plate and radially disposed from the central spindle, a peripherally slotted plate carried by each of the radially disposed spindles, said slotted plates being adapted to prevent the outward sliding movement of the central spindle by partially obstructing the path of movement of the toothed plate, means to rotationally orientate all of the spindles to align the slots of the obstructing plates with the teeth of the centrally located plate to allow an outward movement of the central spindle, and a cam surface on said latter spindle to allow the retraction of the bolts from the locking groove upon said movement of said spindle.
3. A safe comprising a casing, an end plate, and a locking mechanism, said mechanism comprising a locking groove in the casing, a centrally disposed rotatable and slidable spindle carried by the end plate, a plurality of slidable bolts carried by the end plate, the inner ends of said bolts abutting said spindle and the outer ends of said bolts being adapted to extend within the locking groove to secure the end plate to the casing, spring means to urge said bolts inwardly toward said spindle, a circular plate secured to the lower end of said spindle, said plate being peripherally cut away to provide a plurality of teeth angularly spaced from each other in non-uniform relation, a plurality of rotatable spindles carried by the end plate and radially disposed from the central spindle, said spindles being angularly spaced from each other in identical non-uniform relation as the teeth of the spindle plate,

at least one circular plate secured to the lower end of each radially disposed spindle, said plates being of equal size and each having a plurality of peripherally spaced slots complementary in form and size to the teeth of the central spindle plate, said radially disposed spindle plates being adapted to prevent the outward sliding movement of the central spindle by partially obstructing the path of movement of the toothed plate, means to rotationally orientate all of the spindles to align the slots of the obstructing plates with the teeth of the centrally located plate to allow an outward movement of the central spindle, and a cam surface on said latter spindle to allow the retraction of the bolts from the locking groove upon said movement of said spindle.

4. A safe as defined in claim 2 wherein each of the radially disposed spindles has secured thereon another plate of equal size, said additional plate being located above the plurally slotted plate and having a single peripheral slot in

alignment with one of the plurality of slots of the plate therebeneath.

5. A safe as defined in claim 3 wherein each of the radially disposed spindles has secured thereon another plate of equal size, said additional plate being located above the plurally slotted plate and having a single peripheral slot in alignment with one of the plurality of slots of the plate therebeneath.
